UNITED STATES PATENT OFFICE

HERBERT E. METCALF, OF SAN LEANDRO, CALIFORNIA, ASSIGNOR TO THE MAGNAVOX COMPANY, OF OAKLAND, CALIFORNIA, A CORPORATION OF ARIZONA

PHOTO-ELECTRIC TUBE

Application filed April 16, 1928. Serial No. 632,570.

This invention relates to apparatus for use in wireless or wire communications and commercial use for the rectification, amplification and generation of either low or high frequency oscillations.

The object of the invention is to produce a device of this character employing a vacuum tube or vessel and having a film, layer or surface of volatile material, which, under the action of light or external heat, will cause an emission to the anode so as to function in the desired manner without employing the usual hot electrode inside the tube or vessel.

A further object of the invention is to facilitate the manufacture of a rectifier, amplifier or oscillator of the type mentioned.

In carrying out these objects, I employ an evacuated vessel of glass, quartz, or other suitable material, which has contained therein a cathode in the form of a film, layer or surface of a volatile material, such as those metals belonging to the sodium-potassium group connected to the outside by a suitable connection. This film, layer or surface is deposited by means of condensation. There may be contained therein also an anode or collecting device. The state of the interior of the evacuated vessel may be a complete vacuum, or any intermediate stage of gaseous content, or it may be filled after pumping with a gas of the helium group in order to prevent the breaking down of the cathode.

This device is made so as to function in practically the same manner as the well-known two electrode vacuum tube, except that it shall not contain any "filament" or hot electrode inside the tube. The emission from the active and sensitive film, layer or surface is caused either by the action of light falling upon the cathode or the action of heat applied by a heater external to the entire tube. It has been found that emission may be obtained from the cathode to the anode by the use of either light or heat, and that the emission may be controlled by an intermediate electrode, if desired, when the anode is kept at a positive potential. It has furthermore been found that in the manufacture of such a tube special care should be taken to prevent the contamination of the anode by the sub-

stance which is used as cathode in order that it function properly, and the present application discloses a method whereby such contamination is eliminated.

In the preferred method of manufacture, 55 the volatile materials, such as those metals of the sodium-potassium group, are placed on the anode before assembly into the complete tube, and when said anode is heated after assembly into the tube, the volatile materials thereon are vaporized and deposited by condensation on the walls of the tube or on a nearby receptacle for the purpose of acting later as a cathode. The cathode material is first formed upon the anode and by means 60 of heat applied to the anode, such material is evaporated to form the cathode. In this manner the anode is freed from contamination by the cathode material and at the same time the cathode is formed in the shape of a 65 film deposited over the entire inner wall of the tube or other base. In order that the place where connection is made through the glass tube to the anode be effectively insulated from the cathode, shields may be placed 70 to prevent the deposition of cathode material or such areas may be heated during the time of deposition, so that no cathode material will be deposited in those places. By making the anode run through the entire tube with 75 two outside connections a flow of current may be passed through it during manufacture so that they may become hot and thus vaporize and throw off the cathode material. It has also been found that in a tube of this sort 80 when it is set into operation only by the action of light, a portion of the walls of the tube may be cleaned of cathode material by means of heat, thus giving a window whereby light may be admitted to the interior of the tube. 85 In case it is desired that the tube be operated by heat only, such a window is not necessary and the entire tube may be placed inside a heating element which is entirely independent of any electrical connection to the tube 90 itself.

In the accompanying drawings—

Fig. 1 shows a diagrammatic view of the composite filament before the same is inserted in the vessel or tube.

Fig. 2 shows a diagrammatic view of the composite filament in place within the vessel or tube and before the same has been heated to discharge the volatile substance therefrom.

5 Fig. 3 shows a diagrammatic view of the step of heating the composite filament to cause condensation of the volatile material thereon.

10 Fig. 4 shows a diagrammatic view of the tube or vessel after the volatile material has been discharged from the composite filament and deposited upon the walls of the vessel.

15 Fig. 5 shows a diagrammatic view of a modified form wherein a cylindrical member is placed around the composite filament.

Fig. 6 shows a view of a similar form after the composite filament has been heated to cause deposition of the volatile substance upon the cylinder.

20 Fig. 7 shows a modified arrangement wherein the volatile material is placed in a reservoir at one end of the vessel and heated by external means to cause deposition of the material upon the walls of the vessel.

25 Fig. 8 shows a diagrammatic view of a device embodying my invention and employing an intermediate member so as to function after the fashion of the well known three-electrode vacuum tube.

30 Referring in detail to Fig. 1 of the accompanying drawings, I show a non-volatile wire 7 upon which there has been deposited a volatile active substance 8 which is shown merely for clearness in the drawing as being 35 in the form of nodules. It may also be in the form of a smooth coating. Both ends of this non-volatile wire are brought out with two terminals 1 and 2. This portion is sealed into a vessel 10, as shown in Fig. 2. There 40 is a connection 4 on the wall of the tube which will become the means for electrical connection to the cathode surface when it is later formed.

45 A battery 11 is then attached to the terminals 1 and 2 of the non-volatile wire, as shown in Fig. 3, and said non-volatile wire 7 is then heated by the passage of a current. This heat vaporizes the volatile portion 8 of the wire and such volatile material is deposited 50 in the form of a film 5 over the inside walls of the tube, as shown in Fig. 4, thereby forming the cathode. The cathode is then connected through the medium of connection 4. This leaves the non-volatile portion of the 55 entire assembly in the center free of volatile material, as indicated at 6. The two ends 1 and 2 are then joined together to make a third connection 3 which then becomes the anode lead. Referring further to Figure 4, it 60 may be seen that the tube is complete, having a connection 4 to the active cathode surface 5, and a non-volatile wire 6 in the center of the evacuated vessel forming the anode. The surfaces which are not shown covered by 65 cathode material have been cleaned of same

by heat from an outside source or by the use of shields during vaporization.

Fig. 5 shows a slightly different type where a metal base is used, whereon the active material is deposited instead of the walls of the vessel 10. This metal base is indicated at 9, being preferably in the form of a cylinder. The procedure for depositing cathode material thereon is exactly the same as already described. The anode 7 containing cathode material 8 is heated through the medium of the battery 11, as shown in Fig. 6. The active material 8 becoming vaporized is thereupon deposited upon the metal base 9 in the form of an active film or surface 5, leaving the center anode 6 free and uncontaminated from cathode material.

Fig. 7 shows a device of this sort which is made by the vaporization of active material from an outside well 8. This active material may be vaporized by the application of external heat and is deposited by condensation in the form of a film 5 on the walls of a vessel 10, the cathode connection being made at 4. However, in making a device of this sort it is difficult to prevent the anode 6 from being contaminated by condensed cathode material, so by making the anode 6 in the form of a loop or continuous wire, both ends being brought to the outside, the current from the battery 11 may be passed through the anode terminals 1 and 2, heating the anode 6, thereby evaporating from it and cleansing it of all cathode contamination.

Fig. 8 discloses a method whereby an intermediate member may be introduced into this evacuated vessel 10. Either or both the member 15 and anode 6 may be used to deposit the volatile active material. However, it is important that a current be passed through 105 both the anode and the intermediate member 6 and 15, so that they may be effectively cleansed of contamination by cathode material. For this purpose I show batteries 11 and 13. The evacuated vessel in this case 110 would act practically in the same manner as the well known three-electrode vacuum tube.

Various changes in the construction and arrangement of the several parts herein shown and described may be employed without departing from the spirit of my invention as disclosed in the appended claim.

Having thus described my invention, what I claim and desire to secure by Letters Patent is:

In a two-electrode vacuum tube having an evacuated vessel and double terminal anode, the latter having deposited thereon a volatile material sensitive to the action of light, the step of heating the anode to cause the volatile material to be vaporized and deposited in the form of a sensitive film upon the inner wall of the vessel, whereby to form a light sensitive cathode.
